UNITED STATES PATENT OFFICE.

EDMUND C. MORGAN, OF MORGAN PARK, ILLINOIS.

EXCAVATING-MACHINE.

1,175,166.

Specification of Letters Patent. Patented Mar. 14, 1916.

Application filed June 27, 1910. Serial No. 569,174.

To all whom it may concern:

Be it known that I, EDMUND C. MORGAN, a citizen of the United States, residing at Morgan Park, in the county of Cook and State of Illinois, have invented certain new and useful Improvements in Excavating-Machines, of which the following is a specification.

This invention relates to excavating machines, and has for its main general object to provide an improved construction, combination and arrangement of parts in machines of this character.

The particular objects of this invention will appear in the specification and be specifically pointed out in the appended claims, reference being had to the accompanying drawings exemplifying the invention, and in which—

Figure 1 is a side elevation of the rear end of a machine constructed in accordance with the principles of this invention. Fig. 2 is a side elevation of the front end of the same. Fig. 3 is a top plan view of the rear end of the machine. Fig. 4 is a top plan view of the front end of the same. Fig. 5 is a rear end elevation of the same machine. Fig. 6 is a front end elevation of the machine. Fig. 7 is a section on the line VII—VII of Fig. 1. Fig. 8 is a section on the line VIII—VIII of Fig. 2. Fig. 9 is a section on the line IX—IX of Fig. 8. Fig. 10 is a section on the line X—X of Fig. 11. Fig. 11 is a section on the line XI—XI of Fig. 1. Fig. 12 is a fragmentary side elevation taken from the left end of Fig. 11.

In the embodiment shown in the drawings, a support for the excavating machine is provided in the form of a truck comprising the main frame or body 1 suspended from a pair of axles 2, to which are keyed truck wheels 3 which travel on rails 4 for advancing or withdrawing the machine. A motor 5 which is preferably a reversible electric motor provided with a reversing switch 6, is rigidly mounted upon the main frame 1. Armature 7 of said motor (see Fig. 7) is rigid with a main drive shaft 8, which extends longitudinally and centrally throughout the length of the truck frame 1.

As seen best in Fig. 1, the truck wheels are driven in pairs by worms 9 meshing with gears 10, which are freely rotatable about the axles 2. In order to adapt the drive shaft 8 to be thrown into and out of driving connection with the axles 2, a clutch 11 is splined to each axle 2 in such manner as

to be adapted to be moved into and out of clutching engagement with a clutch element rigid with the gear 10. For this purpose a system of levers may be employed (see Fig. 7) which connect with a shifting lever 12 for simultaneously throwing said clutches in and out. Within suitable pedestals carried by the main frame 1 are journaled a pair of parallel shafts 13, to each of which is keyed a spiral gear 14 meshing with a spiral pinion 15 freely rotatable on the drive shaft 8. A clutch 16 splined to the drive shaft 8 is adapted to be shifted into and out of clutching engagement with the pinion 15 by a lever 17, so that the shafts 13 may be driven from the drive shaft when desired. Adjacent the upper end of each shaft 13 is pivotally mounted a supporting plate 17, which is provided with a depending bearing portion 18 journaled in a bracket arm 19 projecting laterally from the upper end of a rigid pedestal 20. To the swinging end of each supporting plate 17 is pivoted at 21 a lower chute section 22, said chute sections being constructed and arranged to provide a central conveying channel when in lateral abutment with each other. Slidably mounted on each lower chute section 22 is an upper chute section 23. For this purpose each lower section 22 (see Fig. 8) is provided with an outer lateral flange 24, while each upper section 23 is provided with a depending flange 25 resting upon the lower section 22. Each upper section is moreover provided with a slide-way 26 for slidably engaging the flange 24. At the upper end of each vertical shaft 13 is rigidly mounted a driving sprocket 27 which drives an endless chain conveyer 28 traveling through each lower chute section, each of said lower chute sections being provided at its lower forward end with a sprocket wheel 29 (see Fig. 2) for mounting the lower end of the conveyer. Adjacent the pivotal support 21, and driven by the conveyer 28, is a sprocket wheel 30 (see Fig. 1) keyed to a short shaft 31 upon the upper end of which is keyed a second sprocket 32 for driving an endless chain conveyer 33 in each upper chute section, each of said conveyers 33 being supported at the outer swinging end of its chute by means of a sprocket 34 (see Fig. 2). Said sprocket 34 is journaled in a scoop or shovel 35 pivoted at 36 to the forward end of each upper chute section, said shovel being provided with a rearwardly projecting arm 37, between which

and the lower end of the chute section extends a tension member 38 which tends to maintain the shovel 35 in alignment with the section, but also permits said shovel to 5 be deflected so as to lie flat upon the floor of the mine, or other place where the machine may be in use.

Referring more especially to Figs. 9, 10, 11 and 12, means for moving each upper 10 chute section over the corresponding lower section is provided by a cam shaft 39, which may be oscillated upon its own axis by means of a crank arm 40. On the shaft 39 are mounted three cams 41, 42 and 43, these 15 cams being operably related respectively to clamping arms 44, 45 and 46. Each of the clamping arms is provided with a strap 47 (see Fig. 10) which extends around and is moved by its particular eccentric, such as 48 20 in Fig. 10. The clamping lever 44 is adapted to impinge upon the bottom of the lower chute section 22 in such manner as to lock the upper and lower sections rigidly together. The clamping lever 45 is provided 25 with a lateral extension 48 which is adapted to be moved into clamping engagement with the downwardly and forwardly moving portion of the conveyer 28 to move the upper section forwardly. The clamping lever 46 30 is provided with a lateral extension 49, which is adapted to be brought into clamping engagement with the upwardly moving portion of the conveyer 28. Eccentrics 41, 42 and 43 are set at such angles as to permit 35 of only one of the clamping levers being operative at the same time.

A spring such as that indicated at 100 in Figs. 1 and 12, may be employed as a centering device so that when the crank 40 is 40 moved in one direction the spring will be stretched, and when moved in the other direction it will be compressed. In either case when the crank 40 is actuated to release the cams the spring will assist in restoring the 45 crank and the cams to initial position. The eccentric cams may be variously arranged, and if desired, the crank 40 may occupy a substantially horizontal position or a position in a plane parallel to that of the conveyer trough to which it is connected. If the latter arrangement is used the spring 100 would act to hold the crank arm in its initial position and would be stretched both 50 when the crank arm is moved up and when it is moved down, that is, to the vertical position shown in Figs. 9 and 10. When the friction of the cams is sufficiently released the spring could be relied upon to bring the cam mechanism back to central or initial 55 position, or in such position that the conveyer chains would be free to move, as desired.

Referring more especially to Figs. 2 and 6, suitable means for breaking down the material to be excavated is provided in the 60 form of an automatically operated pick 50,

which in the embodiment shown is reciprocably mounted in a housing 51 and connected by a pitman 52 with a crank shaft 53, said crank shaft being provided with a bevel gear 54 driven by a driving pinion 55 keyed to the upper end of a shaft 56, said shaft being driven from the conveyer 33 in the upper chute section. Each of the automatic picks is slidably mounted on either of the upper chute sections and may be moved along or rigidly clamped to the section upon which it is mounted by being rigidly secured to either the downwardly or upwardly moving portions of the upper conveyer 33, or to the flange 57 of the upper chute section. 70 For this purpose a cam shaft 58 is provided with eccentric cams 59, 60, 61, which may be successively brought into clamping engagement with the flange 57 and the two portions of the conveyer 33 respectively. As shown in Fig. 8, the pedestal upon which the pick is mounted is provided with a broad flanged face 62, over which both portions of the conveyer 33 are driven so that when either of the cams 60 and 61 are moved into 80 clamping position the conveyer is clamped between the base flange 62 and the eccentric cam, such as 61, as shown in Fig. 8. The shaft 58 is provided with a crank handle 63.

Referring now to Figs. 1 and 2, means for raising and lowering the chutes and conveyers is provided by oscillatable arms 64, which are keyed to a horizontal shaft 65 having a centrally disposed worm gear 66. Meshing with the worm gear 66 is a worm 100 67 freely rotatable on the drive shaft 8, but adapted to be brought into driven connection therewith by means of a clutch 68 which is splined on said shaft 8. (See Fig. 7.) A shifting lever 69 serves to shift the clutch 68 so that the arms 64 may be raised and lowered at will. The outer end of each of said arms 64 is provided with a rounded protuberance or extremity 70 which abuts against the bottom wall of the lower chute 110 section under which it is disposed. Journaled within the forward end of each arm 64 is a guide pulley 71 over which passes a flexible connection or cable 72, each cable being connected to a short arm or bracket 115 73 projecting from the adjacent under chute section. The cables 72 are wound in opposite directions about a drum 73', which is freely rotatable upon the forward axle 2 of the truck. Said drum 73' is provided with a rigidly connected worm gear 74, with which meshes a worm 75 keyed to a short shaft 76. Free to rotate about the short shaft 76 is a gear 77 in mesh with a gear 78 keyed to the drive shaft 8. In order to 120 transmit the movement of gear 77 to the shaft 76, a clutch 79 is provided which is splined to the shaft 76 and adapted to be moved into and out of clutching engagement with a clutch element on the gear 77. A 125 130

shifting lever 80 is adapted to move the clutch 79 into and out of engagement with the clutch on the gear 77 so that the drum 73' may be rotated to swing the sections of the chutes and conveyers about the axes of the respective vertical shafts 13.

It will be seen from this description that the chutes may be extended at will, and that the construction and arrangement of the several parts are such as to leave a central conveying channel shown best in Figs. 3 and 4, for removing the excavated material upwardly and rearwardly. In order to provide convenient and efficient means for loading the excavated material, a loading conveyer is provided preferably by a chute 81 pivoted at 82 to the rear end of the supporting plate 83, (see Fig. 1) said supporting plate being journaled within an arm or bracket 84 projecting from the pedestal 20. Upon the rear end of the chute 81 is rotatably mounted a sprocket 85, about which travels an endless chain or conveyer 86, which is supported forwardly and driven by a sprocket 87 keyed to the vertical shaft 13. In order to adjust the height of the loading chute 81, a screw support 88, which is reciprocably mounted in a bracket arm 89 carried by the truck frame 1, is threaded at its lower end in a worm gear 90, said worm gear being driven by a worm 91 when it is in clutch with a clutch 92 splined to the shaft 8. A shifting lever 93 serves to move the clutch 92 into and out of clutching engagement with the worm 91 so as to raise and lower the chute 81 at will.

As shown in Figs. 1, 3 and 5, the chute plates 81 are connected to the rear frame 118 at 116, 117 by means of the laterally extending bracket strips 114, 115 and 114', 115'. As shown in Figs. 1, 2, 3, 4, 5, 6 and 12, the intermediate chute plates 110, 110' are held in spaced apart position by means of the inwardly extending strips 111, 111' and 104, 104', which are respectively fastened to the sides of the lower conveyer frame at 112, 112' and 106, 106'. The front chute plates 101, 101' are supported by means of the inwardly extending strips 104, 107 and 104', 107' which are respectively fastened at 106, 109 and 106', 109' to the upper sliding conveyer frame 23. It will therefore be seen that when the conveyer frame 23 is moved back and forth the chute plates 101, 101' move with the same, while the chute plates 110, 110' remain relatively stationary. Hooks 102, 103 and 102', 103' on the forward chute plates 101 and 101' respectively are therefore provided to make the sliding fit with the upper edges of the intermediate chute plates 110, 110', as shown particularly in Figs. 2, 4 and 6. It is therefore evident that not only is the conveyer mechanism extensible but the chute for properly confining and directing the ma-

terial while being moved backwardly by the conveyer mechanism, is also extensible.

What I claim is:

1. The combination with a frame, of a chute mounted on said frame, conveyer mechanism for sliding material along said chute, additional conveyer mechanism mounted for relative longitudinal movement with respect to the first-named conveyer mechanism, and a supplemental chute slidably mounted on said first named chute and coöoperating with said additional conveyer mechanism to deliver material into the first-named chute and to the first-named conveyer mechanism.

2. In a machine of the character described, the combination with a support, of a vertical shaft rotatably carried by said support, a chute pivoted at one end on said shaft, an endless chain conveyer in said chute driven by said shaft, a motor operatively connected with said shaft, and means driven by the motor for raising and lowering the outer swinging end of said chute.

3. In a loading apparatus, the combination with a frame, of a chute carried thereby, a second chute slidably mounted on the first chute, a conveyer for sliding material along the second chute and from the same into the first chute, an additional conveyer for directing the material from the second chute, means dependent upon one of said conveyers for moving one of said chutes over the other and along the same in either direction, and means for holding said movable chute in adjusted position.

4. In a machine of the character described, the combination with a support, of a chute carried thereby, a second chute slidably mounted on the first chute, a conveyer for each chute, a motor operatively connected to the lower conveyer, and means operated by the lower conveyer for driving the upper conveyer.

5. In a machine of the character described, the combination of two chutes, one slidably mounted on the other, an endless chain conveyer for each chute, and a pair of rigidly connected sprockets operatively connecting said conveyers.

6. In a machine of the character described, the combination of two chutes, one slidably mounted on the other, an endless chain conveyer for each chute, means carried by one chute for engaging the conveyer in the other chute, to impart relative movement to said chutes, and means for clamping said chutes together, each of said means being rendered inoperative by the operation of the other.

7. In a machine of the character described, the combination of two superposed chutes slidably engaging each other, an endless chain conveyer movable through each chute, means for alternatively locking one

- chute to either band of the conveyer in the other chute, and means for locking said chutes together.
8. In a machine of the character described, the combination of two superposed chutes slidably engaging each other, an endless chain conveyer movable through each chute, a plurality of clamps movably mounted on one chute and adapted respectively to releasably engage either of the bands of the other conveyer and the other chute, and means for selectively operating said clamps.
9. In a machine of the character described, the combination with a support, a motor mounted thereon, a rotatable shaft connected to said motor, a drive sprocket rigid on said shaft, a chute pivoted adjacent one end on said shaft, and provided with a sprocket adjacent to its swinging end, an endless chain conveyer mounted on said sprockets, a second chute slidably mounted above the first chute, an endless conveyer in the second chute, and a pair of rigidly connected sprockets, one of which drives the last said conveyer and the other of which is driven by the first said conveyer.
10. In a machine of the character described, the combination of two chute sections adapted when disposed side by side to form a conveyer channel disposed between the sections, and an endless chain conveyer mounted on each section, said conveyers being provided with adjacently disposed portions traveling in the same direction through said conveying channel.
11. In a machine of the character described, the combination of two chute sections in slidable lateral abutment and pivotally mounted to swing about parallel axes, said sections being adapted together to form a central conveying channel, an endless chain conveyer for each section, each conveyer having a portion traveling through said central channel, and means for swinging said sections about their axes.
12. In a machine of the character described, the combination of two chute sections in slidable lateral abutment and pivotally mounted to swing about parallel axes, said sections being adapted together to form a central conveying channel, an endless chain conveyer for each section having a portion traveling through said central channel, and means for swinging said sections about their axes, said means being adapted to hold them in abutment.
13. In a machine of the character described, the combination of two chute sections in slidable lateral abutment, said sections being movable about the same horizontal axis and about parallel vertical axes, means for swinging each of said sections toward the other section, and means for raising and lowering the outer swinging ends of the chutes.
14. In a machine of the character described, the combination of two chute sections in slidable lateral abutment, said sections being movable about the same horizontal axis and about parallel vertical axes, means for swinging each of said sections, a conveyer for each section, and a loading conveyer to which both of the other conveyers deliver material.
15. In a machine of the character described, the combination with a truck, of a motor and driving shaft, a vertical shaft operatively connected to said driving shaft, a conveyer and chute pivotally movable about the axis of said chute and oscillatory about a horizontal axis, a loading chute with its conveyer for receiving material from the first said chute, means operated by said driving shaft for swinging the first said chute about the vertical shaft, means operated by the driving shaft for raising and lowering the first said chute, means operated by the drive shaft for imparting vertical movement to said loading chute, and means operated by said driving shaft for moving said truck.
16. In a machine of the character described, the combination with a truck of a motor and driving shaft, a vertical shaft operatively connected to said driving shaft, a conveyer and chute pivotally movable about the axis of said shaft and oscillatory about a horizontal axis, a loading chute with its conveyer for receiving material from the first said chute, means operated by said driving shaft for swinging the first said chute about the vertical shaft, means operated by the driving shaft for raising and lowering the first said chute, means operated by the driving shaft for imparting vertical movement to said loading chute, means operated by said driving shaft for moving said truck, and a plurality of clutches whereby each of said operative means may be drawn into and out of driven connection with the motor.
17. A machine of the class described, the combination of a support, a chute carried thereby, a second chute slidably mounted upon the first chute, means for moving one of said chutes over the other, means for clamping the chutes together, and a scoop pivotally connected to the forward end of one of the chutes.
18. A machine of the class described, the combination of a support, a chute carried thereby, a second chute slidably mounted upon the first chute, means for moving one of said chutes over the other, means for clamping the chutes together, a scoop connected to the forward end of one of the chutes, and a tension device between the chute and scoop.
19. A machine of the class described, the combination of a support, a chute carried

thereby, a second chute slidably mounted upon the first chute, means for moving one of said chutes over the other, means for clamping the chutes together, a scoop pivotally connected to the forward end of one of the chutes, and a tension device between the chute and scoop.

20. The combination with a support, of a chute carried thereby, a second chute 10 slidably mounted on the first chute, and a conveyer for each of said chutes, each of said chutes comprising longitudinally extending guides arranged in pairs, the pair of one chute being slidably connected to the 15 pair of the other chute.

21. The combination with a support, of a chute carried thereby, a second chute 20 slidably mounted on the first chute, and a conveyer for each of said chutes, said chutes each comprising a pair of longitudinal 25 guide plates spaced apart, the pair of one chute being slidably connected to the pair of the other chute in substantial alinement.

22. The combination with a support, of a chute carried thereby, a second chute 30 slidably mounted on the first chute, means for holding said second chute in adjusted position relatively to said first named chute, a conveyer mounted in said first named 35 chute, and an additional conveyer mounted in said second chute, each of said conveyers having laterally extending flights extending into said chutes near the bottoms thereof respectively, and each of said chutes comprising a pair of spaced apart guide plates, one pair being slidably on the other and in substantial alinement therewith.

23. In loading apparatus, the combination with a main frame, of a conveyer pivoted 40 to said main frame for vertical and horizontal movement, a supporting arm pivoted to said main frame and extending under said conveyer, gearing associated with said arm for lifting and lowering the same to 45 adjust the position of said conveyer, and rope gearing co-operating with said arm for moving the conveyer laterally.

24. In loading apparatus, the combination with a truck, of a conveyer pivoted thereto 50 for vertical tilting and horizontal swinging movements, a pair of forwardly extending arms pivoted to said truck and supporting the forward portion of said conveyer, worm gearing for adjusting the height of the forward end of the conveyer and locking said pair of arms in adjusted position, and rope gearing associated with said pair of arms and connected to said conveyer to swing the same laterally.

25. In loading apparatus, the combination with a truck, of a conveyer pivoted thereto 55 for vertical and horizontal movements, a pair of levers pivoted to said truck and ex-

tending forwardly under said conveyer into frictional engagement therewith, power 60 mechanism for lifting and lowering said pivoted levers to adjust the elevation of that end of the conveyer remote from the truck, said power mechanism comprising means for holding said conveyer stationary at its adjusted elevation, and additional power mechanism co-operating with said first named power mechanism and with said levers for swinging the conveyer laterally while being held at an adjusted elevation.

26. The combination with extensible conveyer mechanism comprising flights extending toward each other, and movable in the same direction over a predetermined path of travel, a platform at one end of said conveyer mechanism for receiving material, an extensible chute for directing the material along said predetermined path of travel, and means for operating said conveyer mechanism to move the material from said platform to said extensible chute and along the same to a predetermined position.

27. The combination with a movable truck, of a frame connected thereto and inclined therefrom to the ground, chute plates spaced apart and fixed to said frame, an additional frame slideable on said first named frame, a platform pivoted to the forward end of said additional frame and adapted to rest in a horizontal position on the ground, two pairs of flight conveyers, one pair being mounted on said first named frame and the other pair being mounted on the said additional frame, additional chute plates spaced apart and fixed to said additional frame and slidably connected to said first named chute plates, and means for operating said conveyers to remove material from said platform to a predetermined position at the rear end of said first named frame while being guided by the aforesaid chute plates.

28. The combination with a truck, of a conveyer pivoted and swiveled thereto for horizontal and vertical movements, a lever arm under said conveyer and in contact with the latter, power mechanism comprising worm gearing for lifting and lowering said lever arm to adjust the elevation of the outer end of said conveyer, and rope gearing for sliding said conveyer over said lever arm by swinging it on said swivel.

In testimony whereof I have signed my name to this specification, in the presence of two subscribing witnesses, on this 21st day of June A. D. 1910.

EDMUND C. MORGAN.
